BENTON C. ROWELL, DECEASED.

TRAIN-BRAKE-CONTROLLING MECHANISM.

1,193,473.

Specification of Letters Patent.

Patented Aug. 1, 1916.

Application filed August 4, 1913. Serial No. 782,762.

To all whom it may concern:

Be it known that I, BENTON C. ROWELL, a citizen of the United States, residing in Chicago, in the county of Cook and State 5 of Illinois, have invented a new and useful Improvement in Train-Brake-Controlling Mechanism, of which the following is a specification.

This invention relates to improvements 10 in train brake controlling mechanism and is in the nature of an improvement upon my invention disclosed in my copending application No. 579,978 for train instrument for signal systems filed September 1, 1910.

15 One object of the invention is to provide a train brake controlling mechanism which is adapted to be operated by a track instrument or train stop when the latter is at danger, said controlling mechanism being so arranged that when tripped by the train stop, it will first cause a service application 20 of the train brakes and subsequently cause an emergency application of the train brakes if the engineer has not in the interim assumed control of the train.

Another object of the invention is to provide a train brake controlling mechanism of the type above indicated having means under the control of the engineer in the cab, by 25 which the mechanism may be reset after it has been tripped or released by a train stop.

Another object of the invention is to provide a mechanism of the type above indicated arranged so as to prevent the engineer 30 from resetting the controlling mechanism after it has once been released or holding the mechanism closed and set without at the same time applying the brakes.

The invention furthermore consists in the 35 improvements in the parts and devices and in the novel combinations of the parts and devices as herein shown, described or claimed.

In practice, it has been found that it is 40 not always desirable to cause an emergency application of the train brakes when an engineer has run past a train stop or track instrument set against him, but to provide means whereby the engineer may assume control of his train even after the brake controlling mechanism has been tripped or released. With such an arrangement it is 45 also desirable that means be provided which compel the engineer to act and assume control of his train within a predetermined

period after the controlling mechanism has been tripped by the train stop, and such means are provided in the mechanism which I am now about to describe.

In the drawing forming a part of this 60 specification, Figure 1 is a diagrammatic sketch illustrating my improvements and showing the connection of the same with the air brake pipes of a train. Fig. 2 is a vertical sectional view of my improved train instrument which is adapted to be tripped or released by a cooperating track instrument or train stop. Fig. 3 is an enlarged detail sectional view showing more particularly the means governing the releasing of the train 65 instrument valve. Fig. 4 is a plan view of a controlling valve employed with my mechanism. Fig. 5 is a vertical section of the controlling valve, taken substantially on the line 5—5 of Fig. 4. Fig. 6 is a transverse 70 sectional view taken substantially on the line 6—6 of Fig. 5 and Fig. 7 is a detail enlarged sectional view of one of the valves.

In said drawing, the train instrument proper is shown as comprising a casing 10 80 having an inlet 11 at the top thereof adapted to be connected with the train pipe of a train brake system, the interior of the casing being thus always under train-pipe air pressure. At the bottom of the casing 10 is 85 provided a valve seat 12 closed by a vertically reciprocating valve 13, the latter being slidably mounted in brackets 14 which in turn are adapted to be secured to any suitable part of the engine or tender, as by 90 means of bolts 15. The valve 13 is held in closed position against the train-pipe air pressure by a pivoted lever 16, one arm 17 of which engages beneath a washer 18 slidably mounted on the valve stem 19, the washer 18 serving to compress a spring 20 encircling the stem 19. The opposite arm 21 of the lever 16 is held down by a headed plate 22, the latter being normally held in locked position by pawls (not shown) and 95 adapted to be released when the plate 22 is engaged by a track instrument or train stop set at danger. As will be obvious, when the plate 22 is released and lifted upward, the valve 13 will be thereby released and 100 opened. The structure above described and its operation is more clearly and specifically described in my said copending application to which reference may be had.

With the mechanism above described,

which is the same as that described in my said copending application, a tripping of the valve, unless means are provided to prevent it, would cause an emergency application of the brakes since the train pipe would be left open to the atmosphere. However, for the purpose of preventing such emergency application of the brakes at first and to allow a sufficient interval of time within 10 which the engineer may assume control of the train, I provide a slideable lock or detent 24 which is normally in the path of a shoulder 25 formed on the under side of the valve 13 and adapted to prevent the same from 15 opening completely, the lock or detent 24, as shown in Fig. 3, being normally disposed slightly below the shoulder 25. For holding the detent 24 in its normal position, it is provided with a valve 26 normally closing 20 the valve opening 27, said valve 26 being held against its seat only by the full air pressure of the train pipe as hereinafter described. The valve 26 is movable within a chamber 28, the latter normally being under 25 full train-pipe air pressure which is supplied through a valve 29 (more particularly hereinafter described) and passageway 30 communicating with the interior of the chamber 10. When the valve 29 is thus 30 opened, the pressure within the chamber 28 will fall and the valve 26 is so balanced by a spring 33, that upon a decrease of pressure within the chamber 28 below a predetermined amount, it will cause the valve 26 to 35 be opened, thereby drawing with it the detent 24 and permitting the valve 13 to be fully and completely opened, thus causing an emergency application of the brakes. As shown in Fig. 7, the valve 29 is provided 40 with a spring controlled needle valve 34 so disposed that it will permit air to pass downwardly through the valve 29 when the pressure is greater upon the top thereof than on the bottom, but will not permit the escape 45 of air from the chamber 28 through the valve 29. From the preceding description it will be seen that by regulating the amount which the valve 13 is allowed to open, the rate of discharge of air from the 50 train pipe can be governed and the time calculated which will elapse between the first opening of the valve 13 and the time when the pressure above the valve 29 will be reduced sufficiently to permit the latter to 55 open and in this way governing the time which elapses between the service and emergency applications of the brakes.

The means for permitting the engineer to assume control of his train, if he is attentive to duty, without the train being brought to a full stop after the train instrument has been operated, comprise a valve resetting rod 35 which is in the form of a piston rod having a piston 36 secured thereto, the latter 65 being movable within a cylinder 37, said

cylinder 37 being in communication with the train-reservoir pipe 38 by means of pipe 39, the latter having included therein a governing valve 40. The governing valve 40, as shown, comprises a valve casing 41 having 70 alined ports 42 and 43 leading respectively to the reservoir and the cylinder, and a tapered oscillatable plug valve 44 adapted to be operated by handle 45, said plug valve 44 having a passageway 46 therein adapted to 75 establish communication between the ports 42 and 43. From an inspection of the drawing, it will be seen that when the passageway 46 is turned so as to place the reservoir in communication with the cylinder 37, the 80 resetting rod 35 will be elevated, thereby engaging the projection 47 on the valve stem 19 and resetting or closing the valve 13.

In order to prevent the engineer from resetting his train instrument without applying the brakes and at least slowing of the train, and also to prevent him from holding the valve 13 closed without applying the brakes, I provide a pipe connection 48 from the train pipe to a port 49 in the governing 90 valve 40, said port 49 being located at right angles to the ports 42 and 43 and located in the same plane therewith. The plug valve 44 is also provided with a passageway 50 arranged as shown in Figs. 5 and 6 and 95 communicating with the atmosphere at the bottom thereof. The passageway 50 is so arranged that when the reservoir and cylinder 37 are placed in communication with each other, the train pipe will be opened to 100 the atmosphere, thereby causing an application of the brakes which can only be removed by turning the handle 45 and then releasing the brakes by operating the engineer's valve in the usual manner. When the 105 handle 45 is turned to release the brakes, cylinder 37 is opened to the atmosphere through passageway 50 and piston 36 will thereupon drop by gravity, thus providing clearance for the valve 13 and removing 110 resistance to operation of the latter. A resetting of the valve 13 will also cause a resetting of the stop or detent 24 since the projection 47 on the valve stem 19 is provided with a cam face 51 which engages a pivoted 115 lever 52 having its upper end thereof engaging in a recess 53 in the stop 24 and adapted to operate the latter.

Although I have herein shown and described what I now consider the preferred embodiment of my improvements, yet it will be understood that various changes and modifications may be made therein without departing from the spirit of the invention, and all such changes and modifications are contemplated as come within the scope of the claims appended hereto.

I claim:

1. A controlling instrument for train brake systems including, in combination: a

- valve casing in communication with the train pipe and having a valve therein; mechanism for holding said valve normally closed against the train-pipe air pressure; releasing means for said mechanism adapted to be operated by a train stop; a stop normally preventing said valve from opening completely when said releasing means are operated and to thereby permit only a service application of the air brakes; and means for moving said stop to an inoperative position to thereby permit said valve to open fully and cause an emergency application of the air brakes, substantially as specified.
- 15 2. An instrument for controlling train brakes including, in combination: a casing having a valve therein; mechanism for holding said valve normally closed; means for releasing and opening said valve and adapted to be automatically operated; a stop normally preventing said valve from opening to its full extent to thereby cause only a service application of the air brakes; and means, automatically operated, for subsequently moving said stop to an inoperative position after said valve is partly opened, to thereby cause an emergency application of the air brakes, substantially as specified.
3. An instrument for controlling train brakes including, in combination: a casing the interior of which is in communication with the train pipe, said casing having a valve therein; mechanism normally holding said valve closed against the train-pipe air pressure; means, adapted to be tripped, to release and open said valve; a stop normally preventing the valve from assuming a completely open position to thereby cause only a service application of the air brakes; and automatically operated train-pipe air-pressure-governed means for subsequently moving said stop to an inoperative position to thereby permit said valve to open fully and cause an emergency application of the brakes, substantially as specified.
4. An instrument for controlling train brakes including, in combination: a train pipe; a casing communicating therewith having a valve and a port in said casing, said valve normally closing said port; means, adapted to be automatically tripped, for releasing and opening said valve; means normally permitting said valve to open only partially; and timed devices for rendering said means inoperative whereby the valve may assume a completely open position, substantially as specified.
5. A train brake controlling system of the character described including, in combination: an instrument having a valve therein normally closing a port in communication with the train pipe, means controlled in accordance with track conditions for releasing
- said valve, means for stopping the valve when it has opened sufficiently to cause a service application of the brakes only; and means, automatically operated when the air pressure in the train pipe has decreased to a predetermined amount due to said valve being automatically opened, for causing said stopping means to release the valve to cause an emergency application of the brakes, substantially as specified.
6. A train brake controlling system of the character described including, in combination: an instrument having a valve closing a port in the train pipe; mechanism automatically operated when track conditions require for releasing and partially opening said valve; and means for resetting the valve to closed position comprising, a cylinder, a piston having an arm thereon for engaging and moving said valve; an air pipe connecting said cylinder with the reservoir pipe of the train, a valve in said pipe operable by the engineer, and a pipe connection from said valve to the train pipe, said valve having ports therein establishing communication between the train pipe and the atmosphere when the reservoir pipe is in communication with the cylinder, whereby the engineer is prevented from resetting or keeping closed the train instrument valve without applying the brakes, substantially as specified.
7. A train brake controlling system of the character described including, in combination: a train instrument having a valve therein and means controlled in accordance with track conditions for releasing said valve and to open it to cause a service application of the brakes; means, under the control of the engineer, for resetting the valve, and for preventing the resetting of said valve without applying the air brakes, substantially as specified.
8. A train brake controlling system of the character described including, in combination: a train instrument having a valve therein; and means controlled in accordance with track conditions for releasing and partially opening said valve to thereby cause a service application of the brakes only; timed air-pressure-governed means permitting said valve to open fully and thereby cause an emergency application of the brakes; and devices, under the control of the engineer, for resetting said valve to closed position, substantially as specified.
